UNITED STATES PATENT OFFICE.

ALBERT S. HAISLIP, OF FREDERICKSBURG, VIRGINIA.

PISTON TOOL.

Application filed May 22, 1923. Serial No. 640,753.

To all whom it may concern:

Be it known that I, ALBERT S. HAISLIP, a citizen of the United States, residing at Fredericksburg, in the county of Spotsylvania and State of Virginia, have invented new and useful Improvements in Piston Tools, of which the following is a specification.

The tool forming the subject matter of the present application for a patent has been designed especially for the use of automobile mechanics in working upon pistons, although not necessarily restricted to such use.

An important object of the invention is the provision of a novel and improved piston grip and support whereby the tool may be engaged in an ordinary vise without necessitating the removal of the connecting rod from the piston to be worked upon.

A further object of the invention is to provide an improved means for beveling a piston ring receiving groove and aperturing the same to prevent the pumping of oil into the cylinder of the engine when the piston is in use.

The invention also has for an object to furnish a tool of this character which is very simple in construction, highly efficient in practical use, and which may be manufactured and sold at a relatively small cost.

Other objects and advantages of my invention will become apparent as the description proceeds, and in order that the same may be better understood, reference is had to the accompanying drawing forming a part of this specification.

In the drawing,

Figure 1 is a perspective view illustrating a tool constructed in accordance with my invention with a piston having an attached connecting rod positioned therein, the tool being gripped between the jaws of a vise;

Fig. 2 is a plan view with the piston removed;

Fig. 3 is a sectional view on the line 3—3 of Fig. 2;

Fig. 4 is a detail showing the operative position of a bit guiding means, and

Fig. 5 is broken view, partly in section illustrating the piston-revolving means.

Referring specifically to the drawing, wherein the preferred embodiment of the invention is disclosed, and in which like reference characters have been used to designate like parts throughout the several

views, numeral 5 denotes a contractible annulus of brass or other suitable alloy. The normally separated terminal portions 6 and 7 of the annulus are provided with aligned transverse bores for loosely receiving a bolt 8, the inserted end of which is threaded and is received in a nut 9 which is countersunk in the outer side of the annulus terminal 7. The other end of the bolt 8 is formed with a cap 10 with a transverse cross pin 10^a whereby the bolt may be rotated. The cap 10 will of course be rigidly keyed or otherwise attached to the bolt, and it is provided adjacent the outer face of the annulus terminal 6, with a circumferential shoulder 11, which later co-operates with the countersunk nut 9 when the bolt is rotated to draw the terminal portions 6 and 7 of the annulus together in an obvious manner for gripping a piston or other annular objects within the annulus 5.

The annulus 5 is supported upon a substantially arcuate metal strap 12, attachment thereto being made by means of bolts 13 passing through eyes 14 which are integrally projected from the annulus terminal 7 and a diametrically opposite point on the annulus 5. Upon reference to Figs. 1 and 3, it will be noted that the under surface of the strap 12 is provided with a depending projection 15 whereby the device may be gripped between the jaws of a vise 16 as shown in Fig. 1. By making the straps 12 of arcuate form as illustrated it is possible to support a piston 17 within the annulus while the tool is held in a vise without necessitating the removal of the wrist pin 18 with its depending connecting rod from the piston.

Upon the upper surface of the strap 12 above the depending projection 15 is formed, a preferably integral block 20, the front or inner face of which is formed with an arcuate groove 21 for the reception of the annulus 5. The inner surface of the end of the block 20 above the annulus receiving groove 21 will be arcuate as shown in Fig. 2 so as to lie flush with the inner edge of the annulus 5 and not to interfere with the holding of a piston therein. The block 20 serves to reinforce the strap 12 at its point of attachment to a vise and the annulus receiving groove 21 thereof lends rigidity to the strap and annulus connection, relieving strain from the eyes 14 in the event

of considerable pressure upon the diametrically opposite and unsupported portion of the annulus.

A well known remedy for pistons which are found to pump oil, that is, which permit the passage of oil past its rings, is to remove the piston and bevel the lower edge of the bottommost ring receiving groove, drilling said beveled portion with a plurality of apertures whereby any oil reaching the groove may be drained back to the crank case without passing above the groove. These operations heretofore have consumed considerable time, the usual method of securing the beveled edge requiring manual filing thereof or the use of a lathe. The means whereby my tool may be made to perform the beveling and aperturing function will now be described.

20 The block 20 is formed with a transverse threaded recess in its outer face as indicated at 22, this recess having communication with the inner face of the block above the groove 21 thereof, by means of a squared or other angular slot 23 of reduced dimensions, which latter is adapted to receive a slidable block 24.

The outer end of the block 24 is formed with a beveled cutting blade 25 as best shown in Fig. 3, the blade 25 being advanced to cutting engagement with the lower edge of the bottommost piston ring receiving groove by means of a screw 26, the head 27 of which is provided with a plurality of apertures 27^a for the insertion of a nail or pin for rotating the same. The screw 26 carries at its inner end a pin 28 of reduced dimensions which is adapted to extend into the slot 23 for engagement with the rear end of the block 24. In order to take up any looseness of the block 24 in the slot 23, and to prevent displacement of the block when not in use, I have provided a set screw 29 which is inserted in one side of the block 20 for engagement with the block 24.

The operation of beveling the edge of a ring receiving groove of a piston may be summarized as follows:

50 A piston 17 is placed in the annulus as shown in Fig. 1, it being unnecessary to remove the wrist pin 18 with its connecting rod 19. The terminal portions 6 and 7 of the annulus are drawn together to contract the annulus around the lower portion of the piston but not tight enough to prevent rotation thereof by means of handles 30 and 31, the first of which carries a reduced threaded extension 32 which passes through the wrist pin 18 and is inserted in the handle 31. The cutting blade 25 may now be advanced by means of the screw 26 to engagement with the bottom edge of the ring receiving groove of the piston. The upper projecting portion of the cutting blade ex-

tends above the edge of the groove operated upon, and effectually maintains the piston upon the upper surface of the strap 12 within the annulus for rotation thereon. The cutting blade 25 may be progressively fed against the edge of the groove during the rotation of the piston until the edge has been suitably beveled as shown at 33 in Fig. 1. In the event that pistons of various sizes are to be worked upon the lowermost grooves of which are at varying distances from the bottom edges thereof, I have provided the portion of the strap within the annulus with steps 34 upon which such pistons may be placed as are of reduced diameter so as to bring the bottom edge of the lowermost cutting groove in the path of the beveled cutting blade 25. It will be obvious that piston rings or other suitable annular objects may be placed either upon the upper face of the strap or upon the steps 34 for the purpose of elevating pistons so that the cutting blade 25 may engage with the bottom edge of the lowermost piston ring receiving groove. In the event that the piston to be operated upon has had its wrist pin and connecting rod removed, then a wrist pin will be placed upon the reduced threaded extension 32 of the handle 30 after which the handle 31 will be screwed upon the end thereof. The handle 31 may now be inserted through the apertures in the sides of the piston until the wrist pin is in proper position whereupon the piston may be rotated as before, the wrist pin making a snug fit and preventing bending of the reduced extension of the handle 30.

In order to form the transverse apertures 35 in the beveled edge 33 of the piston ring groove, I have provided a finger or segment 36 which is loosely pivoted upon the bolt 8 between the terminal portions 6 and 7 of the annulus. When this finger 36 is in the position shown in Figs. 1 and 2 its inner longitudinal surface forms a continuation of the opposed inner edges of the annulus. Thus when a piston is placed within the annulus the inner longitudinal portions of the finger will lie thereagainst and an oblique bore may be cut in the top of the finger as shown at 37 leading through the longitudinal piston-contracting portion at a point at right angles to the beveled edge 33 of the lowermost piston ring receiving groove. A suitable drill may be passed through the bore 37 for transversely aperturing the beveled edge 33 of the piston in an obvious manner. In order to form these apertures in the beveled edge 33 of the piston at regular intervals, suitable graduations may be made upon the upper edge of the annulus as indicated at 38 in Fig. 2, the numeral "4" there shown upon the upper edge of the annulus indicating that an aperture will be formed at each quarter of the circumference 130

of the beveled edge. The first aperture may of course be formed at any desired point, after which the piston will be rotated until the aperture thus formed registers with the desired graduation on the circumference of the annulus. The drill may then be inserted again into the bore and another aperture formed whereupon it will be turned to register with the graduation of the annulus, the operation being repeated until the required number of apertures are formed. It will be evident that they will be in spaced relation.

Referring to Fig. 4 of the drawing it will be noted that the opposed terminal portions 6 and 7 of the annulus are beveled outwardly from top to bottom as shown at 39, and that the portion of the finger 36 in the path of said terminal portions is angularly reduced in width towards its bolt-receiving end so that when said finger 36 is swung down out of position shown in the drawing the terminal portions of the annulus may be drawn together to a greater extent. However, when the finger 36 is in the position shown in the figures it will serve to prevent the tightening of the annulus to such an extent as to prevent the rotation of the piston 17 therein.

Should it be desired, the tool may be permanently attached by bolts to a work bench so that the annulus 5 will project from the front edge thereof, a slot being cut in the bench to receive the projection 15. As heretofore stated, the block 20 is preferably integral. However, this block may be bolted or otherwise secured to the strap 12 if desired.

From the foregoing description, read in connection with the accompanying drawings, it will be readily apparent that my annulus may be clamped in a vise at the front edge of the gripping jaws thereof so that the annulus will project beyond the same thus permitting the annulus to receive a piston with connecting rod attached. Since the transverse bores of the terminals 6 and 7 of the annulus are greater in diameter than the screw 8, there will be no wear upon the interior portions of said bores and they will not become worn out as would be the case were the member 7 threaded internally. Another important advantage of my means for drawing the terminals 6 and 7 of the annulus together, is that by providing the nut 9 countersunk in the outer face of the terminal 7, it is unnecessary that the operator look at the space between the two terminals or move the piston in order to determine whether or not the piston is clamped in the annulus. When the nut becomes loosened on the screw, its looseness may be felt by simply moving the cap 10, as the bolt is loose in the bores of the terminals 6 and 7.

Should beveling of the lower edges of the upper piston ring receiving grooves of the piston be found desirable, this may be obviously accomplished by placing the piston upper end foremost into the annulus and reversing the block 24 so that it may engage with the inverted lower edge of one of the upper piston ring receiving grooves.

While I have described and illustrated the preferred embodiment of my invention, yet it will be understood that I do not propose to limit myself strictly thereto, since various changes and modifications thereof will immediately suggest themselves to those skilled in the art without departing from the spirit of the invention, the scope of which is defined by the following claims.

I claim:

1. A tool of the character described comprising a work receiving portion for supporting rotatable work, a support for said work receiving portion, and a work reducing and retaining means associated with said support.

2. A tool of the character described comprising a work-receiving portion and a combined work-receiving and retaining means carried by said work receiving means.

3. A tool of the character described comprising a contractible work-receiving annulus forming a bearing for rotatable work, an arcuate support for said annulus and a portion of said support extending inwardly of said annulus forming a work support.

4. A tool of the character described comprising a contractible work-receiving annulus forming a bearing for rotatable work, an arcuate support for said annulus having a work supporting portion, and a combined work-reducing and retaining means associated with said annulus.

5. A tool of the character described comprising a work receiving portion forming a bearing for rotatable work, a support for said work receiving portion having a plurality of work supporting portions, and a work reducing and retaining means associated with said support and means for progressively moving said work reducing and retaining means against said work.

6. A tool of the character described comprising a work-receiving portion for rotatable work, and a work-reducing and retaining means carried by said work-receiving means and means for progressively moving said work reducing and retaining means against said work.

7. A tool of the character described comprising a contractible work receiving annulus adapted for receiving rotatable work of various sizes and constituting a bearing therefor, an arcuate support for said annulus having a work supporting portion, a work-reducing and retaining means associated with said annulus and means for progres-

sively moving said work reducing and retaining means against said work.

8. A tool of the character described comprising a work-receiving annulus, a support for said annulus, a portion of said support extending within said annulus to form a work-support.

9. A tool of the character described comprising a work-receiving annulus, a support for said annulus, a portion of said support extending within said annulus to form a work support and a work-reducing and retaining means associated with said annulus.

10. A tool of the character described comprising a contractible work receiving annulus, an arcuate support for said annulus and extending within said annulus to form a work support, a projecting lug carried by said support adapted for engagement with a vise, medial enlargement carried upon the upper surface of said support, said enlargement having an annulus receiving and retaining portion, and a work reducing and retaining element carried by said enlargement.

11. A tool of the character described comprising a contractible work receiving annulus, an arcuate support for said annulus and extending within said annulus to form a work support, a projecting lug carried by said support adapted for engagement with a vise, medial enlargement carried upon the upper surface of said support, said enlargement having an annulus receiving and retaining portion, and a work reducing and retaining element carried by said enlargement and means for progressively moving said work reducing and retaining means against said work.

12. A tool of the character described comprising a contractible work receiving member, a support for said work-receiving member, reinforcing means carried by said support and engageable with said work receiving member, and work reducing means carried by said reinforcing means.

13. A tool of the character described comprising a contractible work receiving member, a support for said work receiving member, reinforcing means carried by said support and engageable with said work receiving member, and work reducing and retaining means carried by said reinforcing means.

14. A tool of the character described comprising a contractible work receiving member, a support for said work-receiving member, reinforcing means carried by said support and engageable with said work receiving member, and work reducing means carried by said reinforcing means and means for progressively moving said work reducing means against said work.

15. A tool of the character described comprising a contractible work receiving an-

nulus, an arcuate support for said annulus, a work reducing and retaining means associated with said annulus and means for rotating said work in said work receiving portion.

16. A tool of the character described comprising a contractible work-receiving member having spaced terminal portions, contracting means for drawing said terminal portions together, movable means carried by said contracting means between said terminal portions to limit the contractibility of said work receiving member, and a work communicating guide means associated with said movable means.

17. A tool of the character described comprising a contractible work-receiving member having spaced terminal portions, contracting means for drawing said terminal portions together, work reducing means associated with said work receiving means, movable means carried by said contracting means between said terminal portions to limit the contractibility of said work receiving member, and a work communicating guide means associated with said movable means.

18. A tool of the character described comprising a contractible work-receiving member having spaced terminal portions, contracting means for drawing said terminal portions together, a support for said work receiving member and the work, work reducing means carried by said support, movable means carried by said contracting means between said terminal portions to limit the contractibility of said work receiving member, and a work communicating guide means associated with said movable means.

19. A tool of the character described comprising a contractible work receiving member having spaced terminal portions, contracting means for drawing said terminal portions together, work reducing and retaining means associated with said work receiving means, movable means carried by said contracting means between said terminal portions to limit the contractibility of said work-receiving member, and a work communicating guide means associated with said movable means.

20. The combination with a contractible work receiving member having an opening therethrough; of a support for said member, reinforcing means carried by said support and engaging said member, and work reducing means carried by said reinforcing means.

21. A tool of the character described comprising a contractible work-receiving member having spaced terminal portions, contracting means for drawing said terminal portions together, said support extending inwardly of said work receiving member

and having descending work supporting steps, movable means carried by said contracting means between said terminal portions to limit the contractibility of said work receiving member, and a work communicating guide means associated with said movable means.

22. The combination with a contractible work receiving annulus having opposed terminal portions and contracting means for said annulus associated with said terminal portions; of movable finger carried by said contracting means between said terminals for limiting the contractibility of said annulus, said movable finger having a work-communicating tool receiving guide associated therewith.

23. The combination with a contractible work-receiving member having an opening therethrough; of a support for said member, said support extending inwardly of said work receiving member and having descending work-supporting steps, reinforcing means carried by said support and engaging

said member, and work reducing means carried by said reinforcing means, work-reducing means associated with said annulus, and means for moving said work reducing means to work engaging position. 25

24. The combination with a contractible annulus having normally spaced terminals; of a support carried by said annulus and one of its terminals, said support comprising a metal strap having an arcuate offset intermediate its ends, and means associated with said support for engagement in a vise. 30

25. In a device of the character described, an annulus having normally spaced terminals, said terminal having aligned transverse bores therethrough, one of said terminals having an angular recess in its outer face, a nut countersunk within said recess, a bolt extending through said aligned bores and engageable with said nut, and said bolt having a shoulder adjacent one end for engagement with said other terminal. 40

In testimony whereof I affix my signature.

ALBERT S. HAISLIP.
